REUBEN B. HALE, OF SAN FRANCISCO, CALIFORNIA

LIGHTING FIXTURE

Application filed April 4, 1932. Serial No. 602,932.

The present invention relates to lighting fixtures, and more particularly to that class of these devices which is especially designed to reflect and diffuse light so as to obtain the most efficient distribution thereof.

Lighting fixtures for industrial lighting have been developed to a high degree of efficiency in effecting distribution of light from a source in accordance with the various requirements of different specific applications, but such fixtures are not adapted for use in any location where the appearance of the fixture is a material consideration. The reason for this is found in the fact that the conformation of a highly efficient fixture is closely limited by purely technical requirements, and hence any material deviation from the technically indicated outline, in the interests of appearance, leads to a marked loss in lighting efficiency.

From this consideration it appears that no satisfactorily ornamental fixture can effect alone an efficient distribution of the light, and, hence, locations which require an ornamental fixture have lacked satisfactory lighting because of the low efficiency of such fixtures.

It is the primary object of this invention to provide a lighting fixture of ornamental appearance which will at the same time effect highly efficient light distribution.

Another object of the invention is the provision of an ornamental fixture of the type above described in which the choice of a wide variety of external forms is permitted without adverse effect upon the lighting efficiency.

Another object of the invention is the provision of a fixture of the type above described in which a wide variety of technically efficient light distributing devices may be incorporated in the same form of ornamental casing.

Another object of the invention is the provision of an ornamental light fixture casing which will assist the distribution of light by a technically satisfactory light fixture associated therewith.

Other objects of the invention will appear as this description progresses.

A preferred form of the invention, adapt-

ed for certain specific lighting requirements, is shown in the accompanying drawing in which:

Figure 1 is a side elevation of the novel fixture having certain portions cut away to show the structure thereof, and

Figure 2 is a bottom plan view thereof.

The source of illumination may be any well known means adapted for the purpose such as an electric lamp. As shown, it is enclosed in a diffusing reflector of heavy, pressed prismatic glass 1 connected to the central support 2 by any suitable means such as hooks 3 from which, preferably, it is removable for cleaning.

The diffusing reflector shown is of a well known type and of a species shaped particularly for use on low ceilings where the fixtures are to be spaced apart about two times the mounting height of the fixtures. It will be understood that the invention is not considered to be limited to this specific form of diffusing reflector but, for instance in cases where the mounting height above the surface to be illuminated equals or exceeds the spacing of the fixtures, a more conical form of diffusing reflector may be substituted. In this way the most efficient conformation of diffusing reflector or other light source may be selected, attention being paid only to the particular lighting requirements, and the appearance of the fixture being wholly disregarded.

The fixture as shown at 1 is designed to reflect a large part of the illumination from the light source downwardly in a conical beam and to throw a diffused light sidewardly and upwardly. Since such fixtures are purely utilitarian in purpose, the fact that they are sometimes so constructed as to throw spotty shadows on the ceiling above them, is not important in the application for which they are designed, but would be quite objectionable in any application where the general artistic effect is a material consideration. The present invention therefore contemplates an auxiliary casing for such fixtures which will take full advantage of their downward lighting efficiency, leave unimpaired their sideward diffusing effect, and remedy the de-

ficiencies in their upward lighting, at the same time providing an ornamental fixture, the form of which may be varied to suit the general plan of the surroundings in which it 5 is to be used.

The casing here illustrated for accomplishing these purposes, comprises a plurality of angular uprights 4 surrounding the fixture 1 adjacent uprights being connected together 10 at their lower end by channeled members 5. Each upright 4 is also provided at its upper end with a hook or other means whereby it may be detachably connected to members 6 for securing each of the said uprights to the 15 central support 2.

These upright members 4, together with the connecting members 5, form a support for a plurality of translucent glass panels 7, preferably of sand blasted or frosted glass, 20 which serve to conceal the fixture 1 as well as to assist the diffusion of the lateral light therefrom. The lower edge of each panel 7 is received in the groove of one of the channeled members 5 while its upper end is held 25 against inward movement by the diffusing panel 8 supported on projections 9 secured to the upright member 4, as shown.

The entire casing fixture above described is so hung with respect to the fixture 1 that 30 the lower edge of the said fixture will not affect the downward light thrown by the said fixture 1, it being substantially out of the downwardly reflected beam.

It is thus evident that the present invention 35 provides a highly efficient form of ornamental lighting fixture, comprising a light distributing fixture the form of which may be readily changed to secure maximum efficiency under the conditions of use without thought 40 to its appearance, and an ornamental casing the form of which may be widely varied to conform with the artistic requirements of the location in which the fixture is to be used, without thought of its lighting efficiency per 45 se, since it is designed to leave unaffected the primary direct and reflected light of the fixture 1, to leave substantially unaffected, except for a slight enhancement, the secondary or lateral diffused illumination effected by 50 said fixture, and to slightly vary the tertiary or upward diffused illumination provided by said fixture for the purpose of remedying an inherent defect therein which would ordinarily make it undesirable for other than 55 purely utilitarian purposes. At the same time a fixture has been provided having many desirable features of constructional simplicity and strength.

It has been emphasized herein that the various elements of the combination described 60 above are capable of wide variation, both for the purpose of securing various lighting effects and for the purpose of securing an artistic effect in harmony with the surroundings in which the device is to be used, and it

should therefore be understood that the scope of the invention is considered to be limited only by the following claims:

1. In a lighting fixture, a source of light, means associated therewith for giving off a diffused beam and a reflected beam, and a casing for said means having an aperture in the path of said reflected beam and diffusing means in the path of said diffused beam. 70

2. In a lighting fixture, a source of light, means associated therewith for giving off a reflected downward beam, an evenly diffused lateral beam, and an unevenly diffused upward beam, and a casing for said means having an aperture in the path of said reflected beam, translucent material in the path of said evenly diffused beam, and a diffusing plate in the path of said unevenly diffused beam. 75

3. In a lighting fixture, a source of light, a light distributing device associated therewith for projecting beams of differing characteristics in different directions respectively, and an ornamental casing for said device having elements of different character in the path of each characteristically distinct beam 80 projected from said device. 90

4. In a lighting fixture, a source of light, and a light distributing device associated therewith comprising a hood having a polished interior adapted to reflect a portion of the light from said source and translucent sides adapted to diffuse a portion of the light from said source, in combination with a casing therefor having an ornamental translucent portion in the path of the diffused 100 light emanating from said hood and an aperture adapted to pass substantially all light reflected from said hood. 95

In witness whereof I have hereunto set my hand this twenty-eighth day of March, 1932. 105
